FLUID PRESSURE HAMMER

Edward W. Stevens, Detroit, Mich., assignor to
Chicago Pneumatic Tool Company, New York,
N. Y., a corporation of New Jersey

Application January 12, 1931. Serial No. 508,126

8 Claims. (Cl. 121—19)

This invention relates in general to tools of the percussive type actuated by fluid pressure and more particularly to those having a free exhaust from the piston chamber controlled only by the impact piston itself and having an automatically thrown valve controlling the admission of the pressure fluid in alternation to the opposite ends of the piston chamber. It is an improvement upon and further development of the invention disclosed in my copending application, Serial No. 431,680, filed February 27, 1930, involving the use of a simple ring valve mounted directly upon the cylinder itself or on a closure member for the same and moveable transversely 10 of the axis of the cylinder to seat upon and seal ports in alternation with its inner face.

After much experimentation the discovery has been made that the edges of the ring valve need not be closely confined by walls with which the 20 valve edges have sliding contact, as disclosed in my copending application, but that improved operation and a much simplified construction may be secured by mounting the valve in a recess with ample clearance in a direction transverse to the direction of movement of the valve. The valve is then automatically centered in the recess by the pressure fluid which passes over both edges, thereby producing a floating effect upon the valve and practically eliminating frictional 30 resistance to its movement.

Among the objects of the invention are to provide an improved arrangement in which live pressure fluid will pass simultaneously over both edges of a valve of the described type and produce a "floating" or balancing effect upon the valve, to reduce friction and wear upon the valve, to simplify the construction and to lower manufacturing costs, and in general to improve prior devices both in structure and in functional 40 operation.

In order to illustrate the invention concrete embodiments thereof are shown in the accompanying drawings, in which:

Fig. 1 is a longitudinal sectional view of a 45 small hand hammer showing a portion of the handle in elevation;

Fig. 2 is an enlarged detail sectional view of the hammer shown in Fig. 1 with certain unessential elements omitted and with the valve 50 shown in its opposite position;

Fig. 3 is a transverse sectional view substantially on the line 3—3 of Fig. 2;

Fig. 4 is a longitudinal sectional view illustrating the invention as applied to a percussive drill 55 having rotation mechanism for the drill steel;

Fig. 5 is an enlarged detail sectional view showing both piston and valve in different position from that shown in Fig. 4; and

Fig. 6 is a transverse sectional view substantially on the line 6—6 of Fig. 5.

Figs. 1 to 3 inclusive disclose the invention in its essentials only and in a commercially developed tool of the small hand type commonly referred to as a "chipping hammer." It comprises merely four parts, a cylinder 7 providing a piston chamber within which reciprocates a piston 8, the operation of which is controlled by a valve 9, the chamber for which is provided by a closure member 10 secured to cylinder 7 as by a threaded connection. Cylinder 7 has passages 65 11, two in number (Fig. 3), leading to the forward end of the piston chamber and short passages 12 leading to the rear end of the piston chamber both under control of valve 9 as will be presently described. Cylinder 7 also has exhaust 70 ports 13 and 14 through the wall thereof controlled solely by piston 8. Valve 9 is a narrow tubular, annular or ring member which telescopically engages a reduced portion 7a of cylinder 7 and is retained in place by closure member 75 10. Portion 7a is further reduced, eccentrically, at least on one side to provide opposed seats 15 and 16, the former having ports 11a connecting with passages 11 while passages 12 extend directly through reduced portion 7a of the cylinder and seat 16. Hence ports 11a and passages 80 12 are controlled by the inner face of valve 9.

As clearly shown in Figs. 1 and 2 the recess defined by the reduced portion 7a of cylinder 7 and by closure member 10 and in which valve 9 is mounted, is of excess width in relation to the length of the valve. In operation valve 9 maintains a central position within the recess, the pressure fluid, which may be admitted into the valve chamber by passage 17 extending 90 through the grip portion of closure member 10, flows simultaneously and equally over and around both edges or ends of the valve maintaining the latter in a partially balanced condition and keeping it out of contact with the walls which limit the valve recess. Hence the valve is quite free of any frictional resistance to its movement.

To give the pressure fluid easy access to the inner face of the valve both edges or ends may be bevelled inwardly as indicated 95 at 9a in Figs. 1 and 2. Since the cycle of operation of tools having a piston-controlled exhaust and an automatically thrown valve controlling the admission of pressure fluid only is well known to those skilled in the art, description 100 105 110

of the same is deemed unnecessary and is accordingly omitted.

The simplicity and ease of manufacture of the above tool are apparent. A minimum of bores are required in the cylinder and the seats for the valve on the reduced portion 7a are conveniently made since they are on the exterior of the cylinder. An added economy is that identically the same valve may be used for hammers of different length of stroke, the only requirement for maximum efficiency being that the throw of the valve, transverse to the axis of the cylinder, be sufficient to admit the additional quantity of pressure fluid required for the additional length of stroke. This is easily accomplished when valve seats 15 and 16 are ground by changing the eccentricity of one of the seats. Inasmuch as the pressure fluid is arranged to pass freely over both edges of the valve only a very small movement of the latter is required. For example, in the form of the invention shown in Figs. 1, 2 and 3 a hammer with a cylinder providing a piston stroke of $1\frac{1}{2}$ " has a valve movement of only .015, a $2\frac{1}{2}$ " stroke hammer requires valve movement of only .020, and a $3\frac{1}{2}$ " stroke hammer valve movement of .031. The small movement of the valve with the floating effect due to the pressure fluid passing freely over the edges of the same from the body of pressure fluid surrounding the exterior of the valve insures quick action and an almost total absence of wear. Moreover, economy in equipment results from the fact that the same handle and valve may be used on cylinders of different stroke for the hammer piston.

Figs. 4 to 6 inclusive disclose the application of the invention to a different type of fluid pressure percussive tool, namely a percussive drill having automatic means for rotating the drill steel. The drill comprises a cylinder 20 within which reciprocates a hammer piston 21 controlling main exhaust ports 22 and 23 and adapted to impart blows directly to a drill steel 24 supported in a rotary chuck 25 mounted in a front head 26 secured to cylinder 20. The opposite end of the cylinder is closed by a member or support 27 having a reduced portion 27a which together with cylinder ring 28 provides a recess for the narrow tubular, annular, or ring valve 29 conforming to valve 9 of the first described modification. Beyond cylinder ring 28 is disposed a ratchet ring 30 and inwardly of the same and cooperating therewith is rifle bar 31, the splined extension of which projects through and has a bearing in ring 28 and closure 27 and extends into the piston chamber to cooperate with rifle nut 32 secured in the recessed rear end of piston 21. The boss on the rear end of rifle bar 31 has a bearing in a ring 33 in telescoping engagement with handle 34. As piston 21 reciprocates in cylinder 20 rifle bar mechanism 30, 31 and 32 imparts rotation to the piston, which rotation in turn is transmitted by the latter to chuck 25 by the usual splined connection and thence to steel 24 in a well-known manner.

The reduced portion of support 27 is ground to provide opposed seats 35, 36 conforming to seats 15 and 16 of the first-described form of the invention, to be engaged by the inner face of valve 29. Ports in seat 35 lead into a passage 37 having return bends connecting with a passage 38 in cylinder 20 leading to the front end of the piston chamber. Ports in seat 36 open into a passage 39 extending into the rear end

of the piston chamber. Pressure fluid, admitted by a supply conduit (not shown) connected to threaded opening 40 in cylinder 20, has identically the same action upon valve 29 as in the first-described modification, the valve being substantially balanced and "floated" by the simultaneous and equal passage of the fluid over and around both edges thereby centering the valve in the recess and keeping it out of contact with the limiting walls of the same. Both edges of the valve are bevelled toward the inner face as indicated at 29a.

In a drill of the type shown in Figs. 4 to 6 inclusive, it is frequently necessary to "blow" the hole, in order to remove accumulated cuttings and to prevent the same from jamming the drill steel so that it cannot be rotated by the drill mechanism. For this purpose a plunger 41 is arranged to be projected through the cylinder wall to engage valve 29 and hold it against seat 36 so that the pressure fluid will continue to pass through passages 37 and 38 to the forward end of the piston chamber whence it passes along the splines to the piston extension and rotary chuck 25 into the bore of the hollow drill steel 24. Plunger 41 has a flange 42 yieldingly maintained in engagement with closure 43 through the action of coil spring 44. Plunger 41 also has an extension beyond flange 42 terminating in a head 45 adapted to be pressed by the thumb or finger of the operator. By preference closure 43 has an annular flange 43a enclosing plunger head 45 to prevent accidental operation of the latter.

While the invention has been herein disclosed in what are now considered to be preferred forms, it is to be understood that the invention is not limited to the specific details thereof, but covers all changes, modifications, and adaptations within the scope of the appended claims.

I claim as my invention:

1. A fluid pressure percussive tool having a cylinder, a piston reciprocable therein, means providing an annular valve chamber having opposed arcuate seats on the inner wall thereof and ports and passages extending from said seats to the opposite ends of the piston chamber, and an annular valve of less length than said chamber for engaging said seats with its inner face in alternation.

2. A fluid pressure percussive tool having a cylinder, a piston reciprocable therein, means providing an annular valve chamber disposed transversely to the axis of said cylinder and having opposed arcuate seats on the inner wall thereof with ports extending from said seats respectively to one or the other end of the piston chamber, means supplying pressure fluid to said valve chamber, and a ring valve of less length than said chamber for engaging said seats in alternation to control said ports, said valve being maintained in a partly balanced state and centrally of said chamber by the pressure fluid passing over both edges of said valve to reach said ports.

3. In a fluid pressure operated percussive tool, the combination of a ring valve and a support telescoping engaged by the same, said support being somewhat reduced to provide seats engaged by the inner face of said valve in alternation and ports in said seats for control by said valve, said support providing clearance for said valve permitting movement of the latter in two directions angular of each other.

4. In a fluid pressure operated percussive tool,

the combination of a ring valve and a support telescopingly engaged by the same, said support being somewhat reduced to provide seats engaged by the inner face of said valve in alternation and ports in said seats for control by said valve, said support providing clearance for said valve permitting movement of the latter both axially and laterally of said support.

5. In a fluid pressure operated percussive tool, 10 the combination of a narrow tubular valve, a support having a reduced portion telescopingly engaged by said valve, said reduced portion being still further reduced eccentrically to provide opposed seats engaged by the inner face of said valve in alternation and ports in said seats under control of said valve, and a member abutting said support to define the valve recess provided by said reduced portion of said support, said recess exceeding the length of said valve 15 to permit the pressure fluid to pass over both edges or ends of the same and to keep said edges out of contact with the parts of said support and member which limit said recess.

6. In a fluid pressure operated percussive tool, 20 the combination of a narrow tubular valve, a support having a reduced portion telescopingly engaged by said valve, said reduced portion being still further reduced eccentrically to provide opposed seats engaged by the inner face of said valve in alternation and ports in said seats under control of said valve, and a member abutting the reduced end of said support to define a valve recess in excess of the length of said

valve, both edges of said valve being bevelled inwardly towards its inner face to give the pressure fluid convenient access to said last-named valve face.

7. A fluid pressure hammer comprising a cylinder, a hammer piston reciprocable therein, a closure for one end of said cylinder, said cylinder reduced at said closure end and having opposed arcuate seats formed on said reduced portion, ports in one seat leading through the cylinder wall to one end of the piston chamber and ports in the other seat leading through the cylinder wall to the other end of said piston chamber, and a ring valve telescoped over said reduced portion and of less length than the latter for engaging said seats in alternation with its inner face, and means admitting pressure fluid within said closure about said reduced portion of said cylinder. 80

8. A fluid pressure tool having a cylinder, a piston reciprocable therein, said tool providing substantially concentric walls and limiting end walls forming an annular valve chamber, a ring valve in said chamber of such size relative thereto that said valve contacts only said inner wall 100 of said chamber and only with opposed portions of its interior surface in alternation, and means supplying pressure fluid to said chamber, the inner wall of said chamber having ports communicating with opposite ends of said cylinder 105 for control by said valve. 95
